GARMENT HANGER

Gertrude M. Schott, Fond du Lac, Wis.

Application October 3, 1934, Serial No. 746,723

4 Claims. (Cl. 223—93)

The invention relates to improvements in wire garment hangers of the known type having a suspending hook, a pair of downwardly diverging garment supporting rods, and a horizontal rod 5 connected with the lower ends of said diverging rods, and it is the object of the invention to provide an improved hanger in which simple and inexpensive, yet efficient provision is made for holding a garment upon the hanger during transportation, when hung for airing, or when supported for any other purpose.

With the foregoing in view, the invention resides in the novel subject matter hereinafter described and claimed, description being accomplished by reference to the accompanying drawing.

Fig. 1 is a perspective view.

Fig. 2 is a side elevation showing the garment holding arms in operative position in full lines 20 and in released position in dotted lines.

Fig. 3 is a detail horizontal sectional view on line 3—3 of Fig. 1.

Fig. 4 is a detail vertical sectional view on line 4—4 of Fig. 1.

Fig. 5 is a detail disassembled perspective view. A preferred construction has been shown and will be specifically described, with the understanding however, that minor variations may be made within the scope of the invention as claimed.

In the drawing above briefly described, the numeral 5 denotes the suspending hook of the hanger, the numerals 6 refer to the garment supporting rods diverging downwardly from said hook, and 7 is applied to the horizontal rod whose ends are connected with the lower ends of said rods 6, the parts 5, 6 and 7 being all formed from a single length of wire.

At its center, the horizontal rod 7 is bent to provide a loop 8 disposed in a vertical plane, said loop being preferably arched. A one-piece garment-holding wire is centrally bent to provide it with a loop 9 which lies against one side of the loop 8, said loop 9 being vertically elongated. The garment-holding wire is provided with two upwardly diverging arms 10 extending upwardly from the loop 9 and with two garment-holding arms 11 extending from the upper ends of said arms 10 toward the lower ends of the rods 6, the lower ends of said arms 11 being provided with lateral portions 12 which overlie said rods 6 to hold a garment upon the latter. These portions 12 are preferably in the form of curved hooks, covered with tubes 13 of rubber or the like, the coverings serving to prevent the portions 12 from possibly injuring the garment.

The loops 8 and 9 are secured together by a fastener 14 which is preferably in the form of a rivet having a head 15 at one end and a washer 16 at its other end. The fastener 14 passes through the upper end of the loop 8 and passes through the loop 9 at a point spaced upwardly from the lower end 17 of the latter, and said loop end 17 is bent laterally into the lower end of said loop 8. By thus providing the two loops with interlocked portions, the garment-holding wire 10, 11 etc. is held 10 against pivoting about the fastener 14.

When the arms 10 of the garment-holding wire are held in one hand and pushed toward each other as shown in dotted lines in Fig. 2, the garment-holding arms 11 are raised from engagement with the rods 6, allowing the garment to be readily engaged with the hanger. Upon release of the arms 10, these arms and the arms 11 return to normal, so that the hooks or the like 12 effectively hold the garment against slipping from the rods 6.

It will be seen from the foregoing that an exceptionally simple and inexpensive construction has been provided, yet one which will be efficient and desirable. On account of existing advantages for the details disclosed, they may be considered as preferred, but attention is again invited to the fact that minor variations may be made within the scope of the invention as claimed.

I claim:

1. A garment hanger having a suspending hook, two garment supporting rods diverging downwardly from said hook, and a horizontal rod connected to the lower ends of said diverging rods, and a garment-holding wire having two spaced substantially vertical arms connected at their lower ends to said horizontal rod, said garment-holding wire having two oppositely projecting longitudinal arms secured to the upper ends of said vertical arms, said longitudinal arms being provided with lateral portions overlying said diverging rods to hold a garment upon the same, said longitudinal arms being upwardly swingable by pressing said vertical arms together, 45 said vertical arms being positioned for joint gripping in one hand.

2. A garment hanger having a suspending hook, two garment supporting rods diverging downwardly from said hook, and a horizontal rod connected to the lower ends of said diverging rods, the center of said horizontal rod being bent to provide a loop disposed in a vertical plane, a garment-holding wire having a central loop lying against one side of the first named loop, and a 55

fastener passing through and securing said loops together, said garment-holding wire having arms extending upwardly from its loop and having garment-holding arms extending from the upper 5 ends of said upwardly extending arms toward the lower ends of said diverging rods, said garment-holding arms having lateral portions overlying said diverging rods to hold a garment upon the same.

10 3. A structure as specified in claim 2; said loops

having interlocked portions, preventing the garment-holding wire from pivoting about said fastener.

4. A structure as specified in claim 2; said loops both extending below said fastener, the lower end of the second-named loop being bent laterally into the lower end of the first-named loop preventing the garment-holding wire from pivoting about said fastener. 5

GERTRUDE M. SCHOTT. 10
